UNITED STATES PATENT OFFICE.

WILLIAM J. A. LONDON, OF HARTFORD, CONNECTICUT, ASSIGNOR TO THE TERRY
STEAM TURBINE COMPANY, OF HARTFORD, CONNECTICUT, A CORPORATION OF
CONNECTICUT.

FLUID-ACTUATED TURBINE.

992,434.

Specification of Letters Patent. Patented May 16, 1911.

Application filed October 4, 1910. Serial No. 585,240.

To all whom it may concern:

Be it known that I, WILLIAM J. A. LONDON, a subject of the King of England, and a resident of Hartford, in the county of 5 Hartford and State of Connecticut, have invented new and useful Improvements in Fluid-Actuated Turbines, of which the following is a specification.

This invention relates generally to fluid 10 actuated turbines, and particularly to the construction of the rotor or bucket wheel, and has for its object the improvement in the construction of the rotor or bucket wheel of fluid actuated turbines of the type where- 15 in the buckets are arranged in the periphery of the rotor.

The invention is illustrated in the drawings in which—

Figure 1 is a side view of part of a bucket 20 with one side plate removed showing some of the buckets in central section and others in side elevation. Fig. 2 is a sectional view on the line 2, 2, of Fig. 1. Fig. 3 is a top view of one of the buckets.

25 Rotors made in accordance with my invention comprise two side plates *a*, *b*, circumferentially grooved on their opposing surfaces near their outer edges as indicated at *c*, and having a circular row of holes *d* just inside of the groove. The buckets 10 are cast or pressed to shape having a bottom plate 1, a curved rear wall 2, a depending transverse stiffening web 3 and side ribs 4, 4. As will be seen these buckets are ar- 35 ranged one on top of the other in a step for- mation about the periphery of the rotor, and the under side of the bottom of one bucket forms the top of the other bucket, producing a chamber inclosed on all but one side and 40 having a curved rear wall. The side ribs 4, 4, on the buckets fit into the circumferential grooves *c* in the plates, and pins 12 pass through the holes *d* in the plates and through an apertured boss 13 on the buckets, these 45 pins being headed over at their outer ends to tie the plates together. There is thus pro- 50 vided a rotor or bucket wall in which the parts are firmly pressed and interlocked pro- viding a structure which will withstand high speed without serious deflection.

I claim:

1. A bucket member adapted for use in the rotor of a fluid actuated turbine comprising in an integral structure a bottom plate and upstanding flange forming side and rear 55 walls, the latter being curved, and a depending stiffening web transversely of said bottom plate.

2. A rotor comprising a pair of side plates and bucket members arranged in step for- 60 mation between the edges of said plates, each bucket member comprising a chamber open at top and front and having a curved rear wall, the bottom of one chamber forming the top of an adjacent chamber, means 65 for securing said bucket members in place, and a stiffening web on the bottom of each.

3. In a rotor the combination with a pair of side plates, of bucket members arranged in step formation between the edges of said 70 plates, and means for securing them in place, each bucket member being formed in an integral structure, with bottom plate, side and curved rear walls and a depending stiffening web.

4. In a rotor the combination with side plates, of bucket members of integral structure open on top and front and having a curved rear wall and a stiffening web de- 80 pending from the bottom, said buckets being adapted for arrangement one above the other in step formation between said side plates, pins extending between said plates and a boss on the under side of the buckets aper- 85 tured to receive said pins.

5. In a rotor the combination with a pair of side plates having circular grooves in their opposing surfaces, buckets having side ribs fitting in said grooves, and a stiffening web depending from their under side, and 90 pins extending from plate to plate through a boss on said buckets to tie said plates together and hold said buckets in place.

WILLIAM J. A. LONDON.
